UNITED STATES PATENT OFFICE.

JOHN B. EADS, OF MATTOON, ILLINOIS, ASSIGNOR OF ONE-HALF TO
CHARLES E. MCCLURE, OF SAME PLACE.

STEAM-ENGINE.

SPECIFICATION forming part of Letters Patent No. 349,573, dated September 21, 1886.

Application filed April 6, 1886. Serial No. 198,031. (No model.)

To all whom it may concern:

Be it known that I, JOHN B. EADS, a citizen of the United States, residing at Mattoon, in the county of Coles and State of Illinois, have invented certain new and useful Improvements in Steam-Engines; and I do hereby declare that the following is a full, clear, and exact description of the same, reference being had to the annexed drawings, making a part of this specification, and to the letters and figures of reference marked thereon.

Figure 1 of the drawings is a perspective view of my invention; Fig. 2, a side elevation thereof; Fig. 3, a detail view, on an enlarged scale, of the valve-operating mechanism; and Fig. 4, a transverse section taken on line *x* *x* of Fig. 3.

The object of the present invention is to provide a simple and effective means for converting motion in steam and other engines, whereby less friction is produced in transmitting the power to the main shaft than by a crank, a more perfect and certain action of the mechanism for operating the valves is obtained, and the general construction of the device rendered more practicable, which objects I attain by the construction substantially as shown in the drawings, and hereinafter described and claimed.

In the accompanying drawings, A represents the cylinder secured to the main shaft B, which has its bearings in a suitable frame, C, a suitable belt-pulley, D, being secured to one end of the shaft, to which power is communicated from the engine. A spiral groove, *a*, is formed on the periphery of the cylinder A, and is continuous and of such shape as to present a long curve on the return-stroke of piston-rods.

I employ two cylinders, E F, connected together, for double engines, both cylinders transmitting their power on the one and same device—one at dead-point and one at quarter-stroke—one piston having a forward motion while the other piston has a backward motion, thereby working in perfect harmony with each other without any of the usual gearing or connection, except as hereinafter described. The employment of a second cylinder enables it to be used as an automatic brake, and by

applying the two cylinders to the same device it can be used successfully on locomotives.

The piston-rods *b c* of the cylinders E F have on their outer ends heads *d e*, from which projects a suitably-shaped pin to engage with the groove *a* in the cylinder A. The head *d* has grooves in its ends to fit over guides *g*, and the head *e* is rabbeted to fit between similar guides, *h*, so that the heads and piston-rods to which they are attached are guided in their reciprocating motion.

The cylinders E F at their sides are provided with steam-chests G H, respectively, the valve-stems *i k* being thus near in line with the main shaft, which by means of certain mechanism moves said valve-stems. This mechanism consists of two grooved blocks, I K, each having an elongated slot, *l*, through it, and extending from its axis to near the periphery of the block, as shown in Fig. 4. The main shaft *B* extends through the slots in the blocks, and the latter are pivotally connected thereto in any suitable manner that will admit of the blocks having a rocking motion, as shown in dotted lines, Fig. 3, the slots or openings *l* through the blocks also being of such form as to allow of this motion. The position of the blocks I K is controlled by means of a shifting frame, L, operated by a suitable hand-lever, M, or any other desirable or well-known means.

The valve-stem *i* has connected to it a lever, *m*, which is pivoted to an arm, *n*, the lower end of said lever being suitably connected to a rod, *N*. A similar rod, *O*, is attached to the valve-stem *k*, and the rods are flat-sided and pass through correspondingly-formed holes in the shifting frame L, to guide them in their movement. The rods *N O* at their free ends are provided with pins *o*, the pin of the rod *N* engaging with the groove of the block I, and the pin on the rod *O* engaging with the groove of block K.

The shifting frame L is suitably mounted on a support, P, and by shifting the frame or sliding it in the proper direction, as indicated in dotted lines, Fig. 3, the end *p* of the frame and the partition *r* will be brought against the sides of the blocks I K, respectively, and bring them to the position shown in dotted lines.

This change in position of the blocks will bring the grooves thereof in an opposite angle to what they previously were.

As the cylinder A revolves motion is imparted to the piston-rods *b c* by means of the continuous spiral groove *a*, and pins on the heads *d e*, which engage with the groove. The grooved blocks *I K* being connected to the main shaft B of cylinder A, as hereinbefore described, the blocks are carried around with the shaft as it rotates, and the grooves in the blocks being at an angle to a perpendicular will impart to the valve-stems *i k* a reciprocating motion by means of the connections between the valve-stems and blocks.

The mechanism above described for operating the valve-stems possesses many advantages, it superseding the link reverse motion, dispensing with the usual rock-shafts and arms, and all other appliances ordinarily used, thereby greatly reducing the friction.

The blocks *K I* may be formed tapering in cross-section, as shown, or any other desirable shape found best adapted to the purpose, and may be connected to the main shaft B by any well-known means that will admit of the blocks having a rocking motion on the shaft, in order to change the angle of the blocks and grooves therein to give valve motion. The valve-stems *i k* may also be connected to the blocks *K I* in any well-known manner that will give to the stems the required reciprocating motion as the blocks are carried around by the rotary shaft.

It is obvious that many minor changes may be made in the several details of construction without departing from the principle of my invention; and I reserve the right, therefore, to make such changes as come within ordinary

mechanical skill. The cylinder A is increased 40 in diameter, whereby the continuous spiral groove *a* is allowed a more circular return, thereby avoiding the sharp return at the dead-point.

If preferred, a governor can be applied to 45 the lever used for shifting the position of the grooved blocks, thereby adjusting the steam direct in the cylinders.

Having now fully described my invention, what I claim as new, and desire to secure by 50 Letters Patent, is—

1. In a steam-engine, two steam-cylinders and steam-chests connected together, in combination with a cylinder having a continuous spiral groove and mounted on a rotary shaft, 55 means for connecting the piston-rods of the steam-cylinders with the groove, and a shifting mechanism constructed and operating substantially as shown, and connecting the rotary shaft with the valve-stems, substantially as 60 and for the purpose set forth.

2. In a steam-engine, blocks having grooves on their periphery and pivoted to the main shaft of the engine, as shown, whereby they will have a rocking motion thereon, in combination with rods connected to the valve-stems and provided with pins to engage with the grooves on the blocks, and a shifting frame for operating the blocks, substantially as and for the purpose specified.

In testimony that I claim the above I have hereunto subscribed my name in the presence of two witnesses.

JOHN B. EADS.
